UNITED STATES PATENT OFFICE

EUGENE L. SCHERMERHORN, OF GOWEN, MICHIGAN

ROAD SCRAPER

Application filed June 13, 1932. Serial No. 616,884.

This invention relates to road scrapers and is more particularly concerned with road scrapers adapted to be mounted upon and underneath motor trucks and designed so that the scraper blade may be lowered and held by hydraulic power.

It is a primary object and purpose of the present invention to provide a very strong, durable and substantial road scraper unit which may be readily installed upon or applied to the chassis side frame members of a motor truck, and in which the scraper blade may be forced down against the road surface by hydraulic pressure; and wherein the blade is rigidly connected to a rock shaft, there being provided yielding means to permit the blade to ride over rough surfaces or stones in the road, the rock shaft and the hydraulic apparatus moving with the blade when it is yieldingly permitted to move.

Other objects and purposes together with various novel features of construction, operation and arrangements of parts for effectively attaining the ends stated will be understood from the following description, taken in connection with the accompanying drawings, in which,

Fig. 1 is a fragmentary end elevation and partial vertical section of the road scraper of my invention applied to the chassis frame members of a motor truck.

Fig. 2 is a plan view thereof.

Fig. 3 is a fragmentary plan view of one of the hydraulic cylinder units, two of which preferably are used with the road scraper.

Fig. 4 is a rear elevation thereof.

Fig. 5 is a fragmentary vertical section illustrating the mounting of the hydraulic cylinder and the yielding means for permitting yielding movement of the road scraper blade.

Fig. 6 is a fragmentary longitudinal vertical section showing the manner in which the scraper carrying beam may be adjusted to different angular positions, and clamped and secured in any position to which adjusted.

Fig. 7 is a fragmentary under plan view of the rotatable mounting for the scraper rock shaft.

Fig. 8 is a fragmentary vertical section and end elevation of the mountings used in rotatably mounting the rock shaft on and underneath the supporting or carrying beam therefor.

Fig. 9 is a fragmentary elevation illustrating the rock shaft divided and spaced apart at its ends, the two parts being permanently connected by an interposed connecting bar.

Fig. 10 is a view illustrating the construction shown in Fig. 9 at right angles to the plane of said Fig. 9.

Fig. 11 is a transverse section on the plane of 11-11 of Fig. 9, and

Fig. 12 is a view similar to that shown in Fig. 6, illustrating a modification in the adjustable clamping mechanism.

Like reference characters refer to like parts in the different figures of the drawings.

In the construction of road scraper, the same is adapted to be carried on, underneath and transversely of the side chassis frame members 1 of a motor truck. To each of said frame members 1 vertical depending cylindrical posts 2 are connected, the upper ends of the posts being integral with plates 3 which lie alongside of the frame members 1 and are securely yet adjustably connected thereto by U-bolts 4, shown in Fig. 2.

Arc-shaped bars 5, preferably of angle iron, at their ends are formed with sleeves 6 through which the posts 2 may pass, and terminate in tongues 7 (Fig. 2) which may be bolted to the adjacent vertical legs of the members 5 to clamp the sleeves on the posts 2 and thereby make it possible to adjust the bars 5 vertically for limited distances within the range permitted by the length of the posts 2.

A scraper carrying beam or hangerboard 8 is located horizontally underneath the chassis frame and across and underneath the horizontal flanges of the arcuate bars 5. Clamping plates 9 each at one end lie above the horizontal flanges of the bars 5 (Fig. 6) and bolts 10 pass through the beam 8 and the plates. Each plate 9 carries spaced apart upwardly extending integral ribs 11 which extend beyond the other end of the plate 100

and through which a pivot pin 12 passes, having an eccentric 13 rotatably mounted on the pin and from which a handle 14 extends, as fully shown in Fig. 6. The beam 8 and the mechanism carried thereby, hereafter described, may be adjusted to many different angular positions relative to the length of the truck. In changing positions the handles 14 are turned upwardly, whereupon the 10 clamp plates 9 bearing against the horizontal flanges of the bars 5 are relieved sufficiently that the beam may be turned to a different position. Then by turning the handles 14 to the position shown in Fig. 6, the clamping of 15 the ends of the plates 9 against the bars 5 again occurs, holding the beam 8 secured with respect to said bars 5 on which it is mounted.

A rock shaft 15 is located lengthwise of and 20 below the beam 8. The beam 8 preferably is of channel form having an upper horizontal web and downwardly extending flanges, as shown in Fig. 8. A U-shaped member 16 having spaced apart depending legs 16a is designed 25 to fit against the underside of the beam 8 associated with which is an upper half 17 of a bearing, the rock shaft 15 lying between said upper half 17 and the lower half 18 of the bearing. The parts may be 30 assembled in the relation shown in Fig. 8 and bolts passed upwardly through the ends of the bearing and through the downwardly extending legs 16a of the member 16 and thence through the horizontal web of the 35 channel beam receiving nuts at their upper ends.

There are a plurality of these bearing constructions in the length of the rock shaft 40 connected to the beam in the manner described and serving to support the shaft 15 so that it may rock or rotate freely. Should, at any time, any of the bearing constructions need replacement due to breakage, wear or the like, any bearing may be readily removed 45 without necessitating the disconnection of all the bearings and the rock shaft from the beam 8.

Arms 19 are permanently secured to the rock shaft 15 by means of cooperating clamping members 20 with bolts 21 passing through the clamps 20 and the adjacent end portions of said arms 19 (Fig. 1). Between the lower or outer end portions of the arms 19 a supporting plate 22 of metal extends and is permanently secured thereto, to which in turn a scraper blade 23 is secured by bolts; and the blade may be adjusted a limited distance in or out with respect to the arms 19, the supporting plate 22 having a plurality of series of holes (as in Fig. 4) for the bolts which connect the scraper blade thereto to pass through.

Hydraulic power units are mounted, preferably adjacent each end of the beam 8, and connected with the scraper blade to force the same downward. A fixture of metal having

spaced apart sides 24 is pivotally mounted at one end on a block 25 permanently secured to and extending upwardly from the beam 8, the sides 24 being integrally connected by a horizontal web 26. The web 26 is located a 70 short distance above and substantially parallel to the web of the beam 8 and between the two a filler or washer of rubber 27 is located (Fig. 5). Above the web 26 a heavy block 28 of rubber is placed, and a bolt 29 passes downwardly through the web 26, both rubber members 27 and 28, and the beam 8.

A hydraulic cylinder 30, closed at its upper end, is mounted adjacent its lower end on and between the sides 24 of the member described. Trunnions 31 extend from the cylinder 30 and have mounting in bearings 32 at the lower side and at the free ends of the parts 24. The cylinder has a piston therein (not shown) from which a piston rod 33 extends, passing out of the lower end of the cylinder and having a pivotal connection at its lower end to ears 19a extending from an arm 19 (see Fig. 1).

A cross bar 34 is connected to and extends to each side of the upper end of the cylinder 30 and bolts 35 pass through the ends of the bar to which one end of each of the coiled springs 36, under tension, are connected and at their opposite ends are connected to pins or rods 37 which may be extensions of the pivot rod by means of which the piston rod 33 is connected to the arm 19. Such springs under tension serve to lift the scraper blade when free to do so.

Oil or other suitable hydraulic liquid is pumped by any suitable pumping mechanism, not forming a part of the present invention, through flexible conduits 38 (see Fig. 2) to pipes 39, which lie alongside of the front edge of the beam 8, and which at their outer ends connect with flexible conduits 40 leading to the upper ends of the cylinders 30. Pumping oil into the upper ends of said cylinders forces the piston rods downwardly and causes the scraper blade 23 to come against the road surface with a pressure dependent upon the pressure to which the oil is pumped after the edge of the blade engages the road.

In operation, on release of the oil pressure within the cylinders, the force of the springs 36 will force the oil out of the cylinders and through the conduits 40, 39 and 38 and the scraper blade will be lifted to a substantially horizontal position so as not to engage the road or be likely to strike thereagainst. When the scraper is to be used oil is pumped through the conduits 38, 39 and 40 and the scraper forced to its down operative position, as shown in Fig. 1. Should the scraper strike any stones, hard spots in the road or other things which necessitate its lifting to avoid breakage, this is permitted by reason of the connection made from the 120 125 130 scraper blade through the arm 19, piston rod 33 and the piston 30 to the sides 24 of the fixture previously described, which is permitted a limited upward movement by reason of its pivotal connection at one end. Such movement is resisted by the rubber blocks 28 which are yieldable, however, sufficiently to prevent breakage of the parts, and which will automatically act to return 10 the scraper blade to its operative position after it has passed over the obstruction.

The construction described is of a very practical, strong and durable character. The adjustment of the beam 8 is about a vertical axis midway between the sides and ends of the beam. A radius rod structure indicated at 41 is carried around a pivot bolt 42 coincident with such axis, the ends of the radius rod having connection to one end of 20 each of the arcuate members 5. This radius rod construction may be varied in many respects and in fact is not absolutely essential and is of minor importance in connection with the present invention.

25 In Figs. 9 to 12 inclusive, there is shown a construction whereby the rock shaft 15 does not extend the full length of the scraper carrying beam, but is replaced by two rock shafts 15a in axial alinement with each other and 30 spaced apart a distance at their adjacent ends. The two rock shafts 15a are connected together by an interposed flat bar 43 of spring steel inserted at its ends into the ends of the rock shafts 15a together with blocks 44 35 shaped so as to fit within the hollow shafts 15a and against each side of the bar 43. Bolts 45 pass through said blocks and the ends of the bar 43 as shown.

With this construction there may be a limited 40 rocking movement of one of the shafts 15a with respect to the other with a consequent twist or distortion of the spring connecting bar 43. It is to be understood that in such case the scraper blade 23 and the supporting 45 plate 22 will likewise be divided between their ends, each of the rock shafts 15a carrying one-half of the divided blade and supporting plate. With such a construction it is possible to rock one of the shafts 15a farther than the other and thus bring the blade carried by it with greater pressure against the road surface.

In Fig. 12 a slight modification in the 50 clamping structure for adjustably mounting the supporting beam 8 is shown. The eccentric 13 with its supporting handle 14 is replaced by a member comprising a head 13a having an operating handle 14a mounted upon a pivot pin 12a. Instead of the head 13a being mounted eccentrically on its pivot, it carries a roller 46 at its lower side to bear against the upper side of the web of the beam 8. With this construction the clamp may be released and then again forced to operative 55 position for permitting adjustment of the

beam and holding it in any position to which adjusted. The head 13a is provided with a shoulder 47 to control and limit its movement and prevent its passing too far or beyond the position at which the clamping action will be exerted.

The claims appended hereto define the invention which is to be considered comprehensive of all forms of structure coming within their scope.

I claim:

1. In a road scraper construction, a supporting beam, a scraper blade mounted on said beam to be raised and lowered, a member pivotally mounted at one end thereof on said beam, a hydraulic cylinder pivotally mounted on said member at its other end, a piston rod extending from said hydraulic cylinder and connected with the scraper blade and means for yieldingly holding said pivotally mounted member against movement away from the beam.

2. A scraper construction comprising, a horizontal beam, a scraper carried on and below said beam and rotatably mounted to be raised and lowered, a member pivotally mounted at one end on and above said beam, a rubber block located above said member between its ends, a bolt passing downwardly through said rubber block and beam, whereby said member is yieldingly held against movement away from the beam, and hydraulic piston cylinder apparatus rockingly mounted at the opposite end of said member, the piston rod of said hydraulic apparatus connecting with the scraper.

3. A construction containing the elements in combination defined in claim 2, combined with springs under tension extending between said scraper blade and the hydraulic cylinder, said springs being tensioned and elongated on downward extension of the piston rod from the cylinder.

4. A scraper construction comprising a horizontal beam, a rock shaft mounted on and below the beam, rigid arms secured to and extending from the rock shaft, a scraper blade carried by said arms, a member having spaced apart sides and an integral horizontal web connecting the sides located above the beam, means pivotally connecting one end of said member to the beam, yielding compression means located on and above the web, a rod passing through said yielding compression means, web and beam, a hydraulic cylinder mounted for rocking movement at the free end of said member between the sides thereof, and a piston rod extensible from said cylinder connected with an arm carrying the scraper blade.

5. A construction containing the elements in combination defined in claim 4 combined with a cross bar secured to the upper end of the cylinder, coiled tension springs connected one at each end to each end of said bar and

extending downwardly in parallel relation to the cylinder and piston rod and means for securing the lower ends of said springs to the arm to which the piston rod is connected.

6. In a road scraper construction, a horizontal beam, means for supporting the same, said beam being of channel form having an upper horizontal web and depending spaced apart flanges, inverted U-shaped members having downwardly extending legs seated underneath said beam, an upper bearing member seated against each of said U-shaped members, a lower bearing member located against the upper bearing member, a rock shaft between the bearing members, bolts passing through the ends of the bearing members and through the legs of said U-shaped member and the web of the channel member, and a scraper blade carried by said rock shaft.

7. A road scraper construction comprising, a supporting beam, a scraper blade carried by said beam and mounted for raising and lowering, a hydraulic piston cylinder mechanism connected with the blade for lowering the same and for holding it with pressure against a road, means for movably mounting the hydraulic apparatus on the beam, combined with rubber yielding means for normally resisting movement of the scraper away from the road when it is in its lower position, but yielding to permit the blade to pass over obstructions.

8. In a road scraper construction, a chassis frame, a road scraper blade carried on, below and transverse of the frame, means for mounting said blade for turning movement

about a horizontal axis whereby it may be raised or lowered, a hydraulic cylinder, a piston rod extensible from said cylinder connected to said blade, a movably mounted supporting means carrying said hydraulic cylinder, and a rubber block associated with said cylinder carrying means compressible to permit the scraper blade to pass over obstructions in a road when in its lower operative position.

9. In a road scraper construction, a chassis frame, a road scraper blade mounted on, carried by and located transversely below the chassis frame, means for mounting said blade for turning about a horizontal axis whereby the same may be raised or lowered, a piston rod connected with the blade, a hydraulic cylinder into which said piston rod extends, a supporting member for the cylinder carrying the same on which the cylinder is mounted to turn about a horizontal axis, means for mounting said supporting member to turn about a horizontal axis, and yielding means acting on said supporting member resisting movement of the scraper blade away from the road when in its lower position but yielding to permit passage of the blade over obstructions.

10. A road scraper construction comprising, a supporting beam, two rock shafts rotatably mounted on and underneath the beam, arms extending from the rock shafts, scraper blades secured to said arms, hydraulic power means connected with said arms to move the same and yielding means interposed between said rock shafts for the purposes described.

EUGENE L. SCHERMERHORN.
